UNITED STATES PATENT OFFICE.

AUGUST KAZMEIER, OF ULM, GERMANY.

PERAMBULATOR.

No. 853,980.

Specification of Letters Patent.

Patented May 21, 1907.

Application filed July 6, 1906. Serial No. 325,025.

To all whom it may concern:

Be it known that I, AUGUST KAZMEIER, a subject of the Emperor of Germany, residing at Ulm, Würtemberg, in the Empire of Germany, have invented a new and useful Improvement in Perambulators, of which the following is a specification.

The object of my invention is to render the body of perambulators or like carriages readily detachable by unskilled persons and without having to remove loose parts, and so allow of its being stored in limited spaces or separately carried upstairs while, moreover, the body can be secured to a sledge at winter-time. For this purpose I adopt the means shown in the annexed drawing, in which:—

Figure 1 is a side elevation of my improved perambulator with the body partly detached; Fig. 2 is a separate side elevation of the means for detachably securing the body to the undercarriage; Fig. 3 is a section on line A—B of Fig. 2 looking in the direction of the arrow x; Fig. 4 is a plan of Fig. 2.

Instead of bolting the body of the perambulator to the undercarriage or frame, I fix to its underside two longitudinal bars *a* which project a little beyond the body at its rear. At the forward end of the carriage the bars are bent down at right-angles and have a hole *b*. Further, a side slot *c* is cut near the rear end of each bar *a* and a knob *d* may be provided for manipulating the said bars. These bars are so disposed as to correspond with two longitudinal bars *a'* permanently

fixed to the springs or similar parts of the undercarriage. The bars *a'* have projecting pins *e* at their forward ends adapted to engage in the holes *b* of the bars *a* and they have stud-screws *f* which can be made to enter the side slots *c*. The screws *f* are fitted with wing-nuts *g* by which the bars *a* and *a'* are reliably secured together.

When it is desired to detach the body of the perambulator the nuts *g* are loosened and the entire body is then shifted a little to one side so as to disengage the slots *c* from the screws *f* and then pushed forward sufficiently to remove the pins *e* from the holes *b* after which the body can be carried away. For subsequently securing the body to the undercarriage, the pins *e* are pushed into the holes *b*, the screws *f* engaged in the slots *c* and the nuts *g* screwed home.

I claim:

In a perambulator or like carriage a detachable body, two bars fixed to the underside thereof, a perforated angular forward end and a side slot near the rear end of said bar in combination with two corresponding carriage-bars in engagement with the holes of said body-bars, and stud screws near the rear end of said carriage-bars to enter the side-slots of the former bars, as set forth.

AUGUST KAZMEIER.
